Patented Oct. 14, 1913.

UNITED STATES PATENT OFFICE.

JOSEPH F. BUHR, OF DETROIT, MICHIGAN, ASSIGNEE, BY MESNE ASSIGNMENTS, TO
HERMAN B. STEATE AND JOSEPH F. BUHR, OF DETROIT, MICHIGAN.

EXPLOSIVE-ENGINE.

1,075,545.

Specification of Letters Patent.

Patented Oct. 14, 1913.

Application filed February 7, 1911. Serial No. 607,059.

To all whom it may concern:

Be it known that I, JOSEPH F. BUHR, a citizen of the United States of America, residing at Detroit, in the county of Wayne and State of Michigan, have invented certain new and useful Improvements in Explosive-Engines, of which the following is a specification, reference being had therein to the accompanying drawings.

This invention relates to explosive engines, and more particularly to the double cylinder two-cycle type, and it has for one of its objects the provision of an engine of this class in which the cylinder is scavenged or blown-out after each explosion and before fresh gas is admitted into the cylinder.

The invention has, furthermore for its object the provision of a positively-operated valve for controlling the flow of gas into either cylinder, the organization being such that the piston of one cylinder compresses the gas charge for the other cylinder, the controlling valve being furthermore under the influence of a governor.

Further objects of the invention will hereinafter appear and be particularly defined in the claims.

The invention has been clearly illustrated in the accompanying drawings, in which similar characters denote similar parts, and in which—

Figure 1 is a frictional section, and illustrates the manner of applying a governor to the control-valve; and Fig. 2 is a horizontal section on line 6, 6 of Fig. 1.

Briefly stated, the engine is of the two-cycle type and consists of a pair of cylinders, set side by side and connected by a gas-inlet passage which is interrupted by a rotary valve in a gas-receiving chamber from which it receives its supply under compression. Instead of the usual way of permitting the compressed gas to enter the cylinder whenever the pressure in the cylinder has dropped enough to permit it, the gas is kept out of the cylinder until the latter has been scavenged by a flow of fresh air which is also under compression established in the casing by the piston movement under the influence of the explosion. The valve is therefore positively driven and so ported that one cylinder compresses the gas to be used in the other cylinder. The gas-compression chamber of the cylinders are also

connected by a direct passage which is normally shut-off by the control-valve, but the latter may be raised by the governor, under excessive engine-speed, to open this passage so that the compressed gas, or at least a part of it, is simply pumped back and forth without entering the explosion-chamber of either cylinder.

Referring now to the drawings, 15, 16 are a pair of compression-cylinders in which pistons are mounted for reciprocation. The upper portions of the pistons are reduced in diameter, as at 17', 18' and are provided with suitable packing rings so as to constitute piston heads 21, 22 for a pair of explosion cylinders 23, 24 which are preferably formed in one integral casting provided with cooling-jackets.

From the foregoing it will be seen, that each crank operates a differential piston, 75 the lower portion of which leaves an annular chamber in the compression-cylinder, while the upper portion constitutes the active or working piston. As previously stated, the working cylinder is scavenged by fresh air under a pressure which is established also by the piston, the latter being cored out to form a chamber A of considerable length and in open communication at its lower end with the crank chamber, so that when said piston moves upward, fresh air will be drawn into the crank chamber. During the

return or down-stroke of the piston, this fresh air will be compressed in the crank chamber and also within a pipe 31 which opens at its upper end into the top of the explosion cylinder 23, in which the force of the explosion is confined by a spring-actuated valve 32, as will be readily understood.

As the piston travels downward under the explosive force, the pressure naturally decreases, and when this pressure becomes less than that in the air pipe 31, fresh air will enter the cylinder and finally blow out through the exhaust port 33, leaving the cylinder "clean" for the reception of a fresh supply of gas which, as has been stated above, is admitted under pressure established by the piston 18 of the other cylinder 16, and contained within the hollow body of a cylindrical valve 35 which is mounted in a valve chamber 36 and preferably rotated, by gears 37, 38 in fixed ratio to the crank-shaft in any convenient manner.

A supply-pipe has communication with the interiors of the compression-cylinders 15, 16 the gas being sucked in by the downward movement of the pistons. The upward movement of the pistons compresses the gas within the cylinders as well as in channels 43, 44 (which lead into the valve chamber 36 above described) and also within the hollow valve 35, which has a peripheral inlet port 42, and an outlet port 45. During the rotation of the valve 35, the inlet port 42 is brought into register with the channels 43, 44 alternately, while the outlet port 45 communicates in a similar manner with conduits 47, 48 but only 15 at a time when the inlet port 42 is closed and vice versa, the gas being confined under pressure within the valve shell 35 until the cylinder 23 has been scavenged in the manner above described, whereupon the outlet port 45 will admit this gas into the cylinder at a time when its exhaust port has again been substantially closed by the upward movement of the piston 21, so that therefor no waste of gas will occur. In other words: 20 a predetermined quantity of gas is delivered into the engine cylinder each time for the reason that the valve 35 and its chamber 36 constitute in a certain sense a "measuring vessel" of a certain capacity and containing gas under a certain compression, as caused by the piston-movement. Therefore, gas will enter the engine cylinder, until the pressures in cylinder and valve are equalized, whereupon the valve outlet-port is again 25 30 35 shut off and the engine piston also shuts off the cylinder-end of the conduit 47. The same thing occurs in regard to the engine cylinder 24, the gas for which is compressed by the piston in the compression cylinder 15 40 of the other crank.

From the foregoing, it will be understood that the gas and air mixture is as near uniform in its character as it can be obtained, and also that the gas will not be released 45 from its confined condition, until the engine cylinder has been exhausted and scavenged with fresh air, all in properly-timed relation.

Now, inasmuch as the conditions in the atmosphere are variable and therefore cannot help affecting the quality of the mixture, means are provided whereby the amount of the hydrocarbon gas in the valve chamber and its valve may be set in accordance with 50 55 these varying conditions, these means consisting of a device whereby the cubic-contents of the measuring chamber, *i. e.*, the valve chamber and its valve, may be increased or decreased, as is for instance illustrated in Fig. 1, in which the valve chamber is provided with a false head 50 which may be adjusted vertically by a sleeve 51 through 60 which the valve stem passes, and which is connected with an angle lever 52 fulcrumed at 53 and adapted to be secured in position

on a segment 54. Furthermore, the valve itself is adapted to be automatically moved longitudinally of its axis of rotation, in order to maintain the speed of the engine within certain bounds, by virtue of varying the compression of the gas, as follows:— The ports of the passages 43, 44 are in alignment horizontally, so that the lower edge of the valve may coöperate with the lower edges of these ports to establish more or less direct communication between the passages, in which case the gas which is being compressed by one piston may be permitted to pass, in part, into the compression-chamber for the other piston. Hence the gas within the valve and its chamber will be under different states of compression and therefore its actual quantity is less when the valve is in its raised position (shown in Fig. 1) than it is in its "closed-in" position. In order to preserve proper relationship between the valve and its seat I prefer to cut horizontally-alined ports or slots 35' into the diametrically opposite sides of the valve so that the lower edge of the valve-body will always remain end-guided in its vertical movement, as controlled by a governor G which may be of any suitable or desired construction.

Many changes may be made in the particular construction and organization of some of the elements of my improved engine, without departing from the spirit of the invention.

I claim:

1. In a gas engine, the combination with an engine cylinder, and a pressure-gas supply therefor, of a gas-measuring device interposed between said cylinder and said supply, and comprising an inclosed chamber of predetermined capacity, and means for connecting said chamber with the gas-supply and said cylinder, alternately, and means for varying the receiving capacity of said chamber.

2. In a gas engine, the combination with an engine cylinder, and a pressure-gas supply therefor, of a gas-measuring device interposed between said cylinder and said supply, and comprising an inclosed chamber of predetermined capacity, and means for connecting said chamber with the gas-supply and said cylinder alternately, and a false head movable within said chamber for varying the receiving capacity of said chamber.

3. The combination with a pair of spaced cylinders, each comprising a working section and a gas-compressing section, of conduits for connecting the compression section of one cylinder with the working section of the other cylinder, and vice versa, and a device in both of said conduits for completing and interrupting the same alternately, a governor for moving said device to establish direct communication between said com-

pressing sections for controlling the amount of gas passing through said device.

4. The combination with a pair of spaced cylinders, each comprising a working section and a gas-compressing section, of conduits for connecting the compressing section of one cylinder with the working section of the other cylinder, and vice versa, and a device in both of said conduits for completing and

interrupting the same alternately, and means for varying the receiving capacity of said device.

In testimony whereof I affix my signature in presence of two witnesses.

JOSEPH F. BUHR.
